UNITED STATES PATENT OFFICE

FRANKLIN L. LANE, OF BELOIT, WISCONSIN, ASSIGNOR TO YATES-AMERICAN MACHINE COMPANY, OF BELOIT, WISCONSIN, A CORPORATION OF DELAWARE

CUTTER HEAD

Application filed February 21, 1927. Serial No. 169,705.

The present invention pertains to wood-working machines, and has to do particularly with the mounting of the knives in the cutter heads of such machines.

5 The principal object of the invention is to provide a novel device by means of which all of the knives in one set in a cutter head may be retracted or projected simultaneously and to an equal extent. While this improvement 10 may be made use of in many different ways, it is of particular advantage in connection with a cutter head having a set of profile knives and a set of grooving knives, since it permits the grooving knives to be drawn back 15 out of the way while the profile knives are being trued up, and then permits them to be returned quickly and accurately to cutting position after such truing operation.

Another important object is to provide a 20 novel device by means of which the ends of succeeding grooving knives in a cutter head may be adjustably positioned at opposite sides of the median plane of cut whereby to vary the width of the groove being cut.

25 Other objects and advantages of the invention will be evident to those skilled in the woodworking art upon a full understanding of the improvement.

One form of the invention is presented 30 herein for the purpose of exemplification, but it will be, of course, appreciated that the invention is susceptible of embodiment in other structurally modified forms coming 35 equally within the comprehensive scope of the appended claims.

In the accompanying drawings:

Fig. 1 is a top view of a cutter head equipped with the improvement of the invention;

40 Fig. 2 is an edge view of the same;

Fig. 3 is a section, taken on the line 3—3 of Fig. 1; and

Fig. 4 is another section, taken on the line 4—4 of Fig. 1.

45 The cutter head illustrated in the drawings is provided with a set of profile knives 10 and a set of grooving knives 11. The profile knives 10 are clamped against seats 12 on the periphery of the head by means of wedge plates 13 which are drawn up against the sides

of the knives by bolts 14, and the grooving knives 11, which are arranged in alternation with the profile knives, are seated in long holders 15 which are held in deep sockets 16 in the head by means of screws 17 which are turned up against the sides of the holders. The sockets are preferably a little wider than the holders, for a purpose hereinafter explained.

55 The inner ends of the holders 15 are formed into racks 18, and all of the racks mesh with a gear 19 which is journaled centrally of the head on a hub-like portion 20 of the same. The gear 19 may be turned in either direction by means of a suitable spanner wrench which 60 may be engaged in notches 21 formed in a sleeve-like portion 22 of the same.

65 When the screws 17 are loosened, the gear 19 may be turned to retract or project the 70 holders 15 and knives 11 simultaneously and to an equal extent. The knives 10 may be trued up conveniently without removing the knives 11 from the head by merely turning the gear 19 to retract the holders 15 and knives 11 into positions wherein the cutting 75 ends of such knives are inwardly of the line of cut of the knives 10. After the knives 10 have been trued up, the gear 19 may be turned to project the holders 15 and knives 80 11 into their former operative positions, thereby obviating any necessity for individual readjustment of the same.

85 The grooving knives 11 are mounted in the holders at a slight angle to the plane of rotation of the head and the direction of the angle of succeeding grooving knives is alternated from one side of the plane of rotation to the other in order to cut cleanly both sides 90 of the groove in the work. Each of the sockets 16 is provided with two opposed studs 23 which project from the sides of the socket into engagement with the sides of the holder. The engagement between the studs and the holder is had at a point adjacent the inner end of the holder, and is 95 preferably at a point where the holder is tangent to a circle concentric with the head. Such engagement permits the outer end of the holder to be swung laterally about the studs as a pivot. Each of the sockets is also 100

provided with the two opposed screws 17 previously described which project into the socket and engage with the sides of the holder adjacent the outer end thereof, where-
5 by to clamp the holder securely in any de-
sired position to lateral adjustment.

When a narrow groove is to be cut in the work, the two screws 17 associated with each socket are clamped against the holder there-
10 in with the axis of the holder in alignment with the axis of the socket, but, when a wider groove is to be cut, the screws are clamped against the holder with one of the screws advanced into the socket more than the other,
15 whereby to swing the cutting edge of the knife in the holder farther into the work, each succeeding knife being thus canted in an opposite direction.

The body of the cutter head is formed in
20 two parts 25 and 26, and such parts are held in assembled relation to each other by means of screws 27. This sectional construction permits formation of the sockets 16 in an easy manner, by milling them in one face of
25 the part 25 before assembly, and serves, after assembly, to hold the gear 19 against axial movement on the portion 20 of the head.

I claim:

1. In a cutter head, a body having a plural-
30 ity of elongated sockets therein, holders in the sockets, knives in the holders, means connected with the holders for retracting or pro-
jecting all of the holders simultaneously and to an equal extent longitudinally of the
35 sockets, and means for permitting each of the knives to be moved separately longitudinally of the sockets.

2. In a cutter head, a body having a plural-
40 ity of elongated sockets therein, elongated
holders arranged longitudinally within the sockets, elongated knives arranged longitudi-
nally within the holders, means connected with the holders and operable upon rotation
45 to retract or project all of the holders simulta-
neously and to an equal extent longitudi-
nally of the sockets, and means for permitting
50 each of the knives to be moved separately within the holders longitudinally of the
holders within the sockets.

3. In a cutter head, a body having a plural-
55 ity of sockets therein, holders in the sockets provided with rack portions, knives in the
holders, a centrally arranged gear in mesh
with the rack portions of the holders and
operable upon rotation to retract or project
60 all of the holders simultaneously and to an
equal extent, and means serving to clamp
both the holders in the sockets and the knives
in the holders.

4. In a cutter head, a body having a socket
therein, a holder in the socket, a knife in the
holder, means in the socket engaging with
65 the sides of the holder adjacent the inner end
of the same for permitting the outer end to

be swung laterally about such engaging means as a pivot, and other means in the socket engaging with the sides of the holder adjacent the outer end of the same for securing the outer end in any desired position lat-
70 erally of the socket.

5. In a cutter head, a body having a socket therein, a holder in the socket, a knife in the holder, two opposed studs in the socket en-
gaging with the sides of the holder adjacent 75 the inner end of the same for permitting the outer end to be swung laterally about said studs as a pivot, and means in the socket en-
gaging with the sides of the holder adjacent the outer end of the same for securing the 80 outer end in any desired position laterally of the socket.

6. In a cutter head, a body having a socket therein, a holder in the socket, a knife in the holder, means in the socket engaging with the 85 sides of the holder adjacent the inner end of the same for permitting the outer end to be swung laterally about such engaging means as a pivot, and two opposed screws in the socket engaging with the sides of the holder 90 adjacent the outer end of the same for securing the outer end in any desired position laterally of the socket.

7. A knife holder for association with a cutter head, characterized by a slot in which 95 a knife is adapted to be positioned, and a longitudinally extending rack formation with which an operating pinion is adapted to mesh to project or retract the holder with respect to the cutter head.
100

8. An elongated knife holder for associa-
tion with a cutter head, characterized by
longitudinally extending slot between the
sides of which a knife is adapted to be posi-
tioned, and a longitudinally extending rack 105
formation with which an operating pinion is
adapted to mesh to project or retract the
holder with respect to the cutter head.

In testimony whereof I have hereunto sub-
scribed my name.

FRANKLIN L. LANE.
